Ralph V. Sage.

GEO. E. Thackray
ATTORNEY

UNITED STATES PATENT OFFICE.

RALPH V. SAGE, OF PHILADELPHIA, PENNSYLVANIA.

CAR END.

1,245,803.

Specification of Letters Patent. Patented Nov. 6, 1917.

Application filed June 22, 1917. Serial No. 176,300.

To all whom it may concern:

Be it known that I, RALPH V. SAGE, a citizen of the United States, residing in the city of Philadelphia, in the county of Philadelphia and State of Pennsylvania, whose post-office address is Widener Building, Philadelphia, Pennsylvania, have invented certain new and useful Improvements in Car Ends; and I do hereby declare the following to be a full, clear, and exact description of the invention, such as will enable others skilled in the art to which it appertains to make and use the same.

My invention relates to the construction of railroad cars and particularly to the construction of drop end gates for gondola cars.

The object of my invention is to provide an improved end structure for gondola cars, which consists generally of rolled channels riveted together, preferably with the flanges of the adjacent channels facing in opposite directions, and overlapped and riveted together through their contiguous flanges. This construction, besides being simple, is very strong and rigid, and in addition is much more economical than other arrangements now being used, as my door is simply made of commercial rolled channels, requiring no special machinery, presses, nor tools for construction and repair.

In general my invention consists in securing a series of channels together so that the inner surfaces of their flange portions are in contact, the backs of the web portions alternately forming the inner and outer faces of the car end. I may, if desired, use wooden filler planks bolted to the inner sides of the webs of the channels, but I wish it understood that my construction is equally well adapted for use without said filler planks.

Having given a general description of my invention, I will now, in order to make the matter more clear, refer to the annexed sheet of drawings, which forms part of this specification, and in which like characters refer to like parts.

Figure 1 is an elevation of the end of a gondola car embodying my invention; Fig. 2 is a vertical transverse sectional elevation 50 through the end of the car taken on the line II-II of Fig. 1; Fig. 3 is a detail elevation on an enlarged scale of a portion of my car end; Fig. 4 is a detail vertical transverse sectional elevation on an enlarged scale illustrating the manner of riveting the channel sections of the car end together; Fig. 5 is a

detail view of the door hinge; and Fig. 6 illustrates in sectional elevation a slightly modified form of car end, in lowered position, the filler planks being omitted and replaced by sleeves or thimbles on the bolts which secure the hinge straps to the door.

Referring now to the characters of reference on the drawings:—1 indicates the car in general, 2 are the corner angles of the car, and 3 is the angle over the end sill. Safety chain devices 4 are secured to the end sill for chaining together cars carrying double loads. 5 indicates the car end door in general, which consists of a multiplicity 70 of rolled channels alternately arranged with their flanges extending inwardly and outwardly, and secured together so that the inner surfaces of their flange portions are in contact. As the inner slopes of the flanges 75 are the same, this results in a flat door construction or one in which the external surfaces on each side are in the same planes. The channels with their webs forming the outer face of the car end are 6 with inwardly 80 extending flanges 7, while the channels with their webs forming the inner face of the car end are 8 with outwardly extending flanges 9. 10 indicates rivets which pass through holes in the channel flanges and secure them 85 together. Wooden planks 11 are secured to the surfaces of the webs of the channels 6 and 8 by means of bolts 13. These planks contain grooves 12, as particularly shown in Figs. 3 and 4, to enable them to be bolted 90 in place without interfering with the heads of the rivets 10. 14 are hinge straps which are secured to the door by means of bolts and these straps extend through slots 16 in the car floor 15, where they are secured and 95 loosely pivoted to the car frame by the links 17. The drop end 5 when in the upright position is held in place by means of keepers 18, which are bolted to the car end and the latches 19, which are pivotally secured 100 to the corner angles, as shown.

Referring now to Fig. 6, which is a modification of my car end, 20 is a modified form of the hinge strap, which connects with the link 21 and is attached to the car end door 105 by means of bolts 22. 23 are thimbles or sleeves which act as spacers between the hinge strap 20 and the channels 6, whose webs form part of the outer face of the car door.

Although I have described and illustrated my invention in considerable detail, I do

not wish to be limited to the exact and specific details thereof, as shown and described, but may use such modifications in, substitutions for, or equivalents thereof, as are embraced within the scope of my invention, or as pointed out in the claims.

Having thus described my invention, what I claim and desire to secure by Letters Patent is:—

- 10 1. A car end comprising a plurality of rolled channels with the inner surfaces of their flanges in contact and secured together thereby.
- 15 2. A drop end for cars comprising a plurality of rolled channels so arranged that the backs of the web portions alternately form the inner and outer faces of the car end, means for securing said channels together and hinges connecting the car end to the car.
- 20 3. A drop end for cars comprising a plu-

rality of rolled channels so arranged that the backs of the web portions alternately form the inner and outer faces thereof, the flanges of said channels extending alternately outward and inward, means passing through said flanges for securing said channels together, and means for securing the car end in position.

25 4. A drop end for cars comprising a plurality of channels with the sloping surfaces of their flanges in contact so that the backs of the web portions alternately form the inner and outer faces of the car end, filler planks secured to the insides of the webs of said channels, and means passing through the flanges for securing said channels together.

35 In witness whereof I hereunto affix my signature.

RALPH V. SAGE.
